UNITED STATES PATENT OFFICE.

SAMUEL H. WILLIAMS, OF SHOEMAKERSVILLE, PENNSYLVANIA.

IMPROVED WINDOW-SASH FASTENER.

Specification forming part of Letters Patent No. 38,440, dated May 5, 1863.

To all whom it may concern:

Be it known that I, SAMUEL H. WILLIAMS, of Shoemakersville, county of Berks, and State of Pennsylvania, have invented certain new and useful Improvements in Window-Sash Fasteners; and I do hereby declare that the following is a full and exact description thereof, reference being had to the accompanying drawings, and to the letters of reference marked thereon, in which—

Figure 1 is a perspective view, and Fig. 2 is a longitudinal section thereof.

The nature of my invention consists in having an elongated case or open box, A, made of cast-iron or other suitable material, which may readily be fitted into one of the vertical edges of a window-sash.

B B are serrated oval rollers which revolve on the center-pin e, which is properly secured transversely into the lower end of the spring C.

H is a screw, by which the upper end of the spring C is properly secured to the upper end of the case or open box A.

D is a screw, which is properly fitted into the face of case A and passes through the spring C, by which means the spring C may be readily adjusted to the required pressure to sustain the weight of any window-sash at pleasure.

J is a sliding bolt, which forms a self-lock by means of a spiral spring, L, placed on the screw D, which presses against the spring C and the guide-sleeve of bolt J. The screw D also forms a substantial guide for the bolt J, which bolt is properly fitted into the upper end of the case or open box A, and projects through the face of case A, and forms a complete self-lock for a window when closed down.

T is a thumb-latch, which projects through the inner side of the window-sash, and is screwed into the bolt J and operates in a corresponding slot made therefor, by which means the bolt is pressed back and the window-sash raised or let down at pleasure.

In opening a window with this invention the operator merely presses the thumb-latch back and unlocks the window, and simultaneously raises the window-sash upward. In so doing the serrated oval rollers assume the position as represented in dotted lines, Fig. 2. The window being raised to any desirable height, it will remain so by means of the serrations of the oval rollers B B (and the pressure of the spring C) catching and pressing against the window-frame and properly holding the window-sash. In closing the sash down, it is merely pulled down by the hand, the serrated oval rollers B B make a half-revolution until the smooth surface on the opposite side or edge of the rollers slide against the window-frame, and the sash is conveniently closed down, which makes it a very useful and durable machine.

I do not claim the spring C, as there are different devices of springs used for this purpose; but

What I do claim as new and my invention and desire to secure by Letters Patent, is—

The serrated oval rollers B B, in combination with the adjustable screw D, when said devices are used for the purpose as described and set forth.

SAMUEL H. WILLIAMS.
